[57] CLAIM

The ornamental design for a joined plug holder, as shown and described.

DESCRIPTION

FIG. 1 is a front elevational view of a joined plug holder showing my new design;

FIG. 2 is a rear elevational view thereof; and,

FIG. 3 is a right side elevational view thereof, the left side being a mirror image of that shown.

The patterned areas within the rectangular boundaries are intended to represent conventional hook and loop type fastening means, and the broken-line elements are intended to represent conventional stitching.
